United States Patent Office.

GEORGE LOWDEN, OF BROOKLYN, NEW YORK.

Letters Patent No. 96,128, dated October 26, 1869.

IMPROVED VELOCIPEDÉ.

The Schedule referred to in these Letters Patent and making part of the same

To all whom it may concern:

Be it known that I, GEORGE LOWDEN, of the city of Brooklyn, in the county of Kings, and State of New York, have invented a new and useful Improvement in Velocipedes; and I do declare that the following is a full, clear, and exact description thereof, which will enable others skilled in the art to make and use the same, reference being had to the accompanying drawing, forming part of this specification.

This invention relates to a new and useful improvement in velocipedes, and consists in the method in which power is applied for driving it.

In the accompanying drawing—

Figure 1 represents a sectional side elevation, looking from the line $x-x$ of fig. 2.

Figure 2 is a top or plan view.

Similar letters of reference indicate corresponding parts.

This is a three-wheeled velocipede, with the power applied to the rear axle.

C B are the rear or driving-wheels, which are fast on the axle.

D is the front or steering-wheel.

E is a ratchet-wheel, on the axle A.

Power is applied to this ratchet by means of the pawls f and g, the former of which is pivoted to the frame h, and to which the saddle i is attached; the other pawl is pivoted to the frame J, to which the foot-pieces k are attached.

These frames or yokes are supported on the axle on which they work or vibrate in the process of working the pawls.

Their back ends extend back over the axle, and are weighted, so that when the weight is removed from the saddle or from the foot-pieces, they tip down and raise the pawls, and thus allow them to take a new hold.

When the weight of the rider is thrown either upon the saddle or upon the foot-pieces, the pawls act upon the ratchet-wheel, and rotate the axle.

The pawl g is made with a heavy back end, so that its point is kept in constant contact with the ratchet-wheel.

The motion of these vibrating frames h and J is limited in their upward movement by the flexible cords l l, attached to the reach.

M represents the reach, through the back end of which the axle loosely passes.

Through its forward end, the steering-post N passes in the usual manner.

The steering is done by means of a second steering-post, O, in front of the rider, which is provided with a cross-handle, h.

This post also has a cross-bar, q, and the two posts are connected together by means of the rods r r, from the cross-bar to the steering-post N, so that the steering-post N partakes of the motion given the post O.

S is a brake on the steering-wheel, which is operated by means of the cord T, which is wound up by turning the steering-handle p in the post O.

As before stated, motion is given the velocipede by working the pawls in the ratchet-wheel, as the weight of the rider is thrown alternately upon the saddle and upon the foot-pieces.

This operation gives him the motion and exercise of a horseback ride.

No crank is employed, and consequently the vehicle may be started at any point, and the operating parts being attached to and supported by the main axle, there is nothing likely to break or get out of order.

Having thus described my invention,

What I claim as new, and desire to secure by Letters Patent, is—

1. In combination with a velocipede, the ratchet-wheel E, pawls f and g, and yokes h and J, arranged and operating on the axle A, substantially as described.

2. In combination with the ratchet-wheel E and weighted yokes h and J, the reach M, post O, brake S, and rods r, arranged substantially as described, for the purposes set forth.

GEORGE LOWDEN.
